UNITED STATES PATENT OFFICE

ALEXANDER LULKI, OF BERLIN, GERMANY

INDICATOR

Application filed June 12, 1929, Serial No. 370,322, and in Germany August 31, 1928.

The invention relates to an indicator intended for use in conjunction with switches, buttons, fuses and similar apparatus serving to distribute electric current.

5 The object of the present invention is to provide a device of this kind which is in connection with the light signal and which may be used in conjunction with existing switches, buttons, etc., without necessity for making any alterations to the switch or to the electric leads. As well known, electric apparatus are standardized to such extent that alterations thereof for the purpose of fitting a light signal arrangement present considerable difficulties, or may be quite impossible at all under certain regulations issued by the particular authorities.

According to the invention the arrangement is of such nature that the signal, i. e., the lamp, is situated at the edge or in the vicinity of the edge of a base plate, and together therewith constitutes an entirely independent indicator which, when the switch is secured to the wall may be disposed between the wall and the rear part of the switch. The plate is preferably furnished with an edge abutment serving to support the mounting. This edge abutment may at the same time also be employed to hold a resistance which is necessary for the lamp.

In a modified form of embodiment the edge of the plate may be furnished with a hollow beading, in which the lamp is situated behind a break in the beading covered by a window.

35 For the sake of better comprehension the invention will be described in the following in its application to a switch, although it will be perfectly understood that no limitation whatsoever is made in this direction, and that the invention is equally applicable to buttons, fuses and other similar parts serving for switching or controlling electric circuits.

In the arrangement according to the invention it is possible to furnish every existing switch already positioned on the wall with a light signal by clamping the base plate with the light signal between the wall and the switch. In the base plate are situated the necessary leads for feeding the signal with electric current, so that the light

signal need simply be connected in parallel with the switch.

The invention will now be described more fully by way of example with reference to the accompanying drawing, in which

55 Fig. 1 is a general view of the light signal arrangement,

Fig. 2 being a similar view rotated to the extent of 90°, the switch itself being shown in dotted lines.

60 Fig. 3 is the general view of a modified form of embodiment, and

Fig. 4 a similar view to Fig. 3 likewise rotated by 90°.

65 Referring now to the drawing, 1 is a base plate consisting of a suitable insulating material and having at the edge an abutment 2. On the abutment 2 is provided an additional elevation 3, in which is situated the mounting for the lamp 4. This lamp is preferably of the gas discharge type connected across the circuit in such manner that the same burns when the switch is moved on to "off". The leads passing to the lamp 4 are designated by 5 and pass out of the base plate 70 1 at a suitable point to be connected with the switch. The edge abutment 2 also serves to support a resistance 6, which is necessary for a glow lamp. In place of a lamp of the latter type it is naturally also possible to 75 employ any other source of light.

80 Fig. 2 shows the simple method of application of the light signal arrangement in conjunction with a switch 7 of conventional form. The base plate 1 is clamped between the wall 8 and the switch 7 by the usual switch securing screws. The lamp 4 in this arrangement is preferably situated immediately above the switch 7, so that in the darkness the part of the wall on which the switch 90 is mounted may be readily recognized.

85 In the form of embodiment according to Figs. 3 and 4 the base plate 1 is furnished with a hollow beading, the lamp being mounted within the latter. The beading is 95 broken for a certain distance, forming a window through which the light of the lamp is able to pass. In this form of embodiment as shown in the drawing the lamp is situated below the switch 7, and in the same manner 100

as described above indicates the point of the wall at which the switch is mounted. The base plate 1 is secured in the same manner as in the previous embodiment.

5 The base plate 1 may be of any desired form, and thus for example may be constructed in the form of a strip clamped between the switch and the wall. Or alternatively, it is also possible to employ a number of 10 strips proceeding in different directions and if necessary connected with each other.

Buttons, fuses, electric door openers and similar arrangements may be illuminated in the same manner. By the use of glow lamps 15 it is possible to employ the device as desired for all voltages, so that in accordance with the invention an independent unit is produced capable of being employed with existing switches or the like in the most simple 20 manner without any alteration whatever.

The holes shown in the plates, strips, etc. in the drawing enable the ground plate or the like to be secured by the same screws employed for holding the switch.

25 As stated above, I do not limit myself to the particular forms of embodiment shown, and various modifications may be made without departing from the spirit of the invention as described above and set forth in the 30 appended claim.

What I claim as new and desire to secure by Letters Patent is:

In an indicator, an electric wall switch a lamp adapted to burn when the said switch 35 is in the "off" position, a base plate adapted to be disposed between the rear part of the said switch and the wall to which the said switch is secured, and an edge abutment on the said base plate adapted to receive the 40 said lamp.

In testimony whereof I have affixed my signature.

ALEXANDER LULKI.
